UNITED STATES PATENT OFFICE.

REUBEN HALEY, OF MOUNDSVILLE, WEST VIRGINIA, ASSIGNOR TO THE FOSTORIA GLASS COMPANY, OF SAME PLACE.

DESIGN FOR A GLASS TRAY.

SPECIFICATION forming part of Design No. 34,620, dated June 4, 1901.

Application filed June 27, 1900. Serial No. 21,855. Term of patent 7 years.

To all whom it may concern:

Be it known that I, REUBEN HALEY, a citizen of the United States, residing at Moundsville, in the county of Marshall and State of West Virginia, have invented and produced a new and original Design for Glass Trays, of which the following is a specification.

In the accompanying drawings, which make part of this specification, Figure 1 is a representation of the design in plan, and Fig. 2 a section on line X X of Fig. 1.

My design consists of a panel X, surrounded by a string of pearl beads B and having bow-knots b b at or near the ends of the

panel. A is an outer rim of flowers combined 15 with scrollwork C.

It is apparent that this design is also applicable to plaques and other similar articles.

Having described my invention, I claim—

The design for a glass tray, substantially 20 as shown and described.

Signed at Moundsville this 18th day of June, 1900.

REUBEN HALEY.
